UNITED STATES PATENT OFFICE.

FRANK C. RINSCHE, OF DETROIT, MICHIGAN, ASSIGNOR TO BURROUGHS ADDING MACHINE COMPANY, OF DETROIT, MICHIGAN, A CORPORATION OF MICHIGAN.

ADDING-MACHINE.

1,243,763.

Specification of Letters Patent. Patented Oct. 23, 1917.

Application filed February 21, 1914, Serial No. 820,127. Renewed March 28, 1917. Serial No. 158,113.

To all whom it may concern:

Be it known that I, FRANK C. RINSCHE, a citizen of the United States, residing at Detroit, in the county of Wayne, in the State 5 of Michigan, have invented a certain new and useful Improvement in Adding-Machines, of which the following is a specification.

The present invention relates to the paper-carrying equipment of an adding and listing machine, and the principal object is to provide an improved construction for automatically returning a sheet of paper to the starting point, in cases where several lists 10 of figures are to be printed in parallel vertical columns. The invention pertains particularly to the matter of control of the automatic paper returning means, and in this connection provides for effecting the return 15 in conjunction with a tabulating or columnar shift of the paper carriage, this being accomplished (in the form of embodiment of my invention here illustrated) by depressing a key which first trips a detent for releasing a paper-returning spring, and then, when permitted to rise upon removal of finger pressure, releases the paper carriage 20 so that the latter will be shifted by its spring to another columnar position. Provision is 25 also made for automatically effecting the release of the paper-returning spring when the paper has been advanced to a certain extent, e. g., as determined by the complete rotation of a wheel in gear with a roller 30 platen. In addition to this, provision is 35 made for optional release of the paper-returning spring at any time without accompanying or ensuing columnar shift of the carriage, and irrespective of the extent to 40 which the paper may have been advanced. Furthermore, the paper-returning mechanism may at any time be disconnected from the platen and the paper adjusted by hand through the turning of said platen under 45 control of a detent roll such as commonly employed to regulate line-spacing.

I have here shown the invention as applied to an adding and listing machine of the well-known Burroughs type (see prior Patents 50 504,963 and 505,078, issued September 12, 1893) though it is to be understood that the invention is not limited to employment in this particular type of machine.

Of the drawings which accompany and

form part of this specification, Figure 1 represents in left side elevation, a machine of the Burroughs type having my invention embodied therein, certain familiar parts of said machine being omitted for the sake of more clearly illustrating other parts intimately associated with the added mechanism of the present invention; Fig. 2 is a rear elevation of the machine with some parts broken away to better illustrate those beyond; Fig. 3 is a perspective view of certain parts which appear in rear elevation at the lower central portion of Fig. 2; Fig. 4 is a left side elevation of the paper carrying structure, with some of the parts broken away in order to better illustrate the normal condition; Fig. 5 is a vertical section taken substantially on the line 5—5 of Fig. 4; Fig. 6, is a vertical section taken on the line 6—6 of Fig. 2, and illustrating a condition the reverse of that illustrated in Fig. 4; Fig. 6^a shows some of the same parts at a different stage in the operation; Fig. 7 is a view on the same order as Fig. 6 but taken on a section line farther over to the right and otherwise differing from Fig. 6 in illustrating a condition resulting from depression of the tabulating key, whereas Fig. 6 illustrates a similar condition resulting from complete rotation of a wheel geared to the roller platen; Fig. 8 is a fragmentary top 85 plan view; Fig. 9 is a view similar to Fig. 7 illustrating release of the paper returning spring by operation of the special hand lever provided for the purpose and appearing in plan view in Fig. 8; Fig. 10 is a similar view 90 illustrating the effect of disconnecting the paper-returning spring from the roller platen; Fig. 11 is a front elevation of the left-hand portion of the paper-carrying structure; Fig. 12 is a section taken substantially 95 on the line 12—12 of Fig. 11; Figs. 13 and 14 are elevations of bell mechanism showing different conditions in operation; Fig. 15 is a plan view of the same; Fig. 16 comprises perspective views of parts thereof detached; 100 Fig. 17 is a perspective view of a paper holding structure; Figs. 18 and 19, sections on lines 18—18 and 19—19 of Fig. 17; Fig. 20 comprises perspective views of parts thereof.

Detailed description of the adding and listing machine proper is unnecessary because of its being so thoroughly familiar to those skilled in the art through disclosures

of the above-mentioned and numerous other prior patents and through extensive marketing of the machine. It will suffice, in this regard, to point out by reference to Fig. 1, that type plates 618 coöperate with a roller platen 10 to print amounts determined by manipulation of keys 221; and that oscillation of the shaft 100 effects step-by-step line-spacing advance of said roller platen through familiar connections such as are illustrated in Patent No. 913,738 issued March 2, 1909 and Patent No. 929,056 issued July 27, 1909.

The main frame of the paper carriage is designated by the numeral 17, the same being mounted as usual to slide upon a track-bracket 17^a secured to the back plate of the machine. There is attached as usual to this frame of the paper carriage a tape or band 18, which winds upon a spring drum 19 constantly tending to shift the carriage to the left. A rock rod 20 is journaled in the lower part of said frame and carries a series of adjustable tabulating fingers 21 which, through engagement with the shoulder of a stop plate 22 on the said back plate of the machine, determine the columnar positions of the carriage in a familiar manner. I shall later on describe a special releasing arrangement for the tabulating fingers 21, which arrangement provides for the carrying out, of one of the objects above stated, to wit, that of first releasing the paper-returning spring and then releasing the paper carriage.

The roller platen 10 is mounted, as usual, in a cradle 12, pivoted upon the carriage frame 17 so as to provide for swinging the platen into and out of printing position. In carrying out the present invention I pivot upon the left hand side plate of said cradle at the point 12^a (Fig. 4) a plate 13, which constitutes the main support for the paper returning mechanism. There is screwed into the central portion of this plate a stud 13^a (Fig. 5), upon which stud there is journaled a sleeve 23, and upon this sleeve there is journaled a gear wheel 24 adapted to mesh with a pinion 10^b secured upon the left hand trunnion of the roller platen. I preferably interpose anti-friction balls 25 between the said gear wheel and sleeve, the latter being grooved to accommodate said balls and a similar groove being formed in the gear wheel by a beveled edge of the web thereof and a similar edge of a plate 24^a, riveted to said web, as shown in Fig. 5.

There is formed integral with the web of said gear wheel a drum 24^b, within which is arranged a coiled spring 26 secured at its outer end to the drum and at its inner end to the sleeve 23. The latter is formed at its inner end with a ratchet flange 23^a with which coöperates an escapement palette

27 for regulating the tension of the spring in a familiar manner (dotted lines Fig. 4, see also Fig. 8).

Obviously the spring, when under tension, tends to rotate the gear wheel and when the latter is in mesh the pinion 10^b, tends to reversely rotate the platen. The arrows in Fig. 4 indicate the directions of rotation of these parts which the spring tends to effect, and of course the direction of rotation of the platen is such as to run backward paper between it and the feed roller 11, which frictionally engages the platen in the usual manner.

Passing now to the matter of control of the aforesaid spring, there is secured upon the left-hand trunnion of the roller platen a V-toothed wheel 10^c, such as commonly employed upon roller platens for regulating the line-spacing under hand-turning, and a pawl or detent 27^a (Fig. 4) normally engages said wheel to prevent backward turning of the platen by the spring. This pawl or detent is in the nature of a lever pivoted intermediate its ends at 27^b and held up as to its forward end by a spring 27^c (see Figs. 4, 6 and 7).

Obviously, advance of the roller platen through the usual line-spacing mechanism will result in winding the spring 26, by reason of the platen pinion 10^b turning the gear wheel 24 in a direction opposite that indicated by the arrow adjacent said gear wheel in Fig. 4, and it will be equally obvious that return rotation of the platen and gear wheel will be prevented by successive engagement of the pawl 27^a with the teeth of the wheel 10^c.

Treating first of the release of the spring in connection with lateral shift of the paper carriage, a link 28 is pivotally hung from the forward arm of the detent lever 27^a and slotted at its lower end to embrace a stud 29 secured in an arm 29^a, which is fastened to the rock rod 20 at the right hand end thereof, as the parts are seen in Fig. 2. The slot 28^a is provided in the said link to permit disengagement of the detent from the V-toothed wheel independently of the tabulating rock rod 20 (as hereinafter described). Obviously rocking of the rod 20 to disengage one of its fingers 21 from the stop plate 22 will result in disengaging the detent 27^a from the wheel 10^c and thus releasing the spring 26 so that the platen will be immediately run backward and the paper returned for the beginning of a new list.

The means for rocking the rod and thereby releasing the carriage for columnar shift, are of the following description (Figs. 2 and 3): Adjacent the stop plate 22 a lever 30 is pivotally mounted on the base frame of the machine having a U-shaped lateral branch 30^a extending under the stop plate

and up in front of the same to present a horizontal edge substantially flush with that of the said plate at the base of the latter's stop shoulder 22^a (Fig. 3). This vertical portion of the U-shaped branch of the lever is formed with a stop shoulder 30^b, slightly offset with respect to the stop shoulder of the plate and adapted to engage the finger 21 and hold back the carriage after the finger has been disengaged from the shoulder 22^a. Thus when the lever 30 is lifted, it lifts the tabulating finger and disengages it from the stop shoulder 22^a; but the finger then becomes engaged with the stop shoulder 30^b, there being a very slight movement of the carriage taking the finger beyond the stop shoulder 22^a so as to prevent its reengaging the same when the lever 30 drops. The latter is engaged by the rear end of a lever 32, which is pivoted intermediate its ends on a frame stud 32^a (Fig. 1) and coupled at its forward end to a key 33, which protrudes to the left of the keys 221 at a convenient place for manipulation. A spring 34 connects the rear arm of said lever to the base of the machine and upholds said key and depresses the lever 30. Finger pressure applied to the key will obviously lift the said lever 30 and effect the result already explained as to the release of the paper-returning spring and disengagement of the tabulating finger from the regular stop plate 22, but continued detention of the carriage by engagement of the finger with the shoulder 30^b. Upon release of the finger pressure the lever 30 drops and the carriage is released and propelled by the spring-drum 19 and tape 18 to a new columnar position which is determined by engagement of the next finger 21 with the stop plate 22.

The machine as thus far described will be seen to greatly expedite tabulating work by providing for return of the paper and shift to a new column, as a result of the mere touching off of a depressible key, the paper being always returned to the same position so that the listing of each column will begin along the same horizontal line.

Referring next to the matter of notifying the operator when the last of a predetermined number of operations has been performed, there is screwed into the end of the stud 13^a a second stud 70 (Fig. 5) upon which is loosely mounted a sleeve 71 carrying a bell 72. The latter is perforated to embrace a screw-threaded reduced outer portion of the sleeve 71 and is clamped against the shoulder of said sleeve by a thumb nut 72^a. The bell is engaged with a slot 71^a in the said sleeve so as to rotate therewith when the latter is rotated through engagement with the gear wheel 24. Such engagement is effected through the medium of a radial arm 71^b of the sleeve, bent over toward said gear wheel and formed at its extremity

to interlock with the teeth thereof. The sleeve is slidable upon the stud 70 so that by pulling out upon the knob 72^a the arm 71^b may be disengaged from the gear wheel and then by turning the knob any desired setting can be had to predetermine the number of operations of the machine. To this end the periphery of the bell along the inner edge thereof is inscribed with a scale, as clearly shown in Fig. 11 (see also Fig. 2), and the plate 18 has an outward and downwardly turned arm 13^d (Fig. 11) which is formed with an index finger 13^e adjacent said scale. A spiral spring 75 tends to engage the arm 71^b with the gear wheel, said spring surrounding a reduced portion of the stud 70 within a recess of the sleeve and bearing at one end against a shoulder of the latter and at the other against a head on the outer end of the stud, all as clearly shown in Fig. 5.

The index arm 13^d above mentioned, besides being formed with the index finger or pointer 13^e is formed adjacent thereto with a long finger 13^f beveled on both sides (Figs. 13 and 14) said finger extending inwardly past the edge of the bell for the purpose of coöperating with a bell-striking mechanism. This mechanism comprises a lever 77 (Fig. 13) pivoted at 78 to the arm 71^b, and a trip lever 79 pivoted at 80 to the said lever 77, said trip lever adapted to coöperate with the finger 13^f. The lever 77 has formed with it or rigidly secured to it a resilient stem 81 extending in a curve on the inner side of the bell and carrying at its extremity the bell-striker or clapper 82. A spring 83 connects an arm of said lever 77 with a stud 84 upon the arm 71^b, tending to throw the bell-striker or clapper outward. Another spring 85 connects said stud with one end of the lever 79 tending to throw a double beveled projection 79^b thereof outward. Normally an extension 79^c of said lever 79 strikes against the boss of the arm 71^b where the lever 77 is pivoted and limits the action of the spring 85.

In the rotation of the gear wheel 24 and the accompanying line-spacing, the forward side of the beveled projection 79^b eventually encounters the rear side of the beveled end of the finger 13^f. Owing to the radial relation between the pivot of the lever 79 and the point of engagement of these beveled edges and also the angle of said edges, the continued turning of the gear wheel and arm 71^b does not result in any turning of the lever 79 upon its pivot but does result in the turning of the lever 77 and the retraction of the clapper or striker 82 against the tension of the spring 83, said lever 77 being slotted at 77^a to embrace the stud 84 for the purpose of permitting a limited swinging. Fig. 14 illustrates this condition. When the point of the projection 79^b passes the point of the finger 13^f the spring 83 takes effect, throw-

ing the lever 77 back to its normal position. The resultant concussion between the lower end of the slot 77^c and the stud 84 causes the resilient clapper stem 81 to be thrown out 5 with a percussive effect against the bell.

It is desirable to avoid a second sounding of the bell when the gear 24 reverses carrying the arm 71^b back with it. That is the purpose of the particular arrangement 10 above described. Thus, the projection 79^b having been carried up in front of the finger 13^c, then upon backward movement of the gear wheel, there will be a camming action under this changed relationship between 15 these parts, which action rocks the lever 79 upon its pivot without again rocking the lever 77, and therefore without again striking the bell.

It is customary to set the bell two steps in 20 advance of the limit of operations to be performed so that, after the itemizing operation at which the bell sounds, there may be the usual blank or spacing operation followed by a totaling operation.

25 Taking up next the matter of automatic release of the paper-returning spring independently of the above-described tabulating devices and as a result of the extent of advance of the roller platen, this in the present instance, results from the gear wheel 24 completing a rotation, and is chiefly advantageous to prevent overwinding of the spring, though it can be availed of for the purpose of effecting automatic release of the 30 paper-winding spring according to previous setting of the gear-wheel by the bell-index. Said gear wheel has affixed to its web a lateral projecting lug 24^c (Fig. 5) which is adapted, under rearward turning of said 35 wheel, to stop its movement and under forward rotation of said wheel to trip the detent 27^a. The normal condition is illustrated in Fig. 4, said lug being engaged with a vertical shoulder 35^a (dotted lines) of an 40 arm 35 pivoted at 35^b to the plate 13. A horizontal shoulder 35^c of said arm engages the upper side of said lug to limit the downward movement of the arm. The latter in rear of its vertical shoulder has a cam edge 45 35^d (dotted lines Fig. 4; full lines Fig. 6) adapted to be acted upon by the lug 24^c (Fig. 6), when the gear wheel 24 completes a rotation, whereby the arm 35 is lifted and the detent 27^a disengaged from the wheel 50 10^c. The connection for effecting this is in the form of a link 36 slotted at its lower end to embrace a stud 27^d carried by the rear arm of the detent lever 27^a, said link being pivotally coupled at its upper end to the arm 55 35. Since the latter is located on the outer side of the plate 13 and the detent lever 27^a on the inner side, said plate is slotted at 13^c to accommodate the stud 35^e which connects the arm 35 and the link 36. It will be understood of course, that the slot at the lower

end of the link is for the purpose of permitting movement of the detent lever independently of the link 36, as in the case of disengaging said detent from the wheel 10^c by the tabulating key, as before described.

70

In neither case should the detent 27^a return to engagement with the platen wheel 10^c until the paper has been run all the way back. In use of the tabulating key this can of course be taken care of by simply holding down the key until the paper has been completely run back. In order to insure this in the case of the automatic tripping of the detent by the lug 24^c when the said key is not used, the following construction is 80 employed: The arm 35 is extended in rear of its pivot and formed with a V-shaped extremity 35^e, which co-operates with a roller 37^a upon an arm 37 pivoted to the plate 13 and drawn forward by a relatively strong 85 spring 38 (Fig. 6). Obviously the roller by engaging one side or the other of the V-shaped extremity 35^e will maintain the arm 35 in one shifted position or the other, it being understood of course that the spring 38 90 is superior to the spring 27^c which tends to return the detent 27^a to engagement with the wheel 10^c.

90

Through devices next to be described, the gear lug 24^c is itself caused to restore the 95 arm 35 to a stopping position just ahead of the completion of the return rotation of the gear. There is pivotally hung from a stud 39^a at the upper end of the plate 13, an arm 39 which co-operates with said lug, 100 said arm being connected by a spring 40 to another arm or link 41 mounted at its forward end at the same stud 39^a and upon its rear end upon a stud 35^f fastened in the rear extension of the arm 35. Normally, the spring 40 holds the arm 39 in engagement with a stop stud 41^a on the arm 41, as shown in Fig. 4, the rearward extension of the arm 35 being elevated and the roller 37^a engaged with the under side of the V-shaped 110 extremity 35^e thereof so that the forward end of the arm 35 is maintained in engagement with the lug 24^c. Normally, the front edge of the arm 39 is flush with the shoulder 35^a, as shown in Fig. 4, and so remains 115 until, as the gear wheel 24 completes a rotation accompanying advance movement of the roller platen, its lug 24^c strikes a rearwardly protruding nose 39^c on the rear side of the arm 39 and swings said arm forward stretching the spring 40, as illustrated in Fig. 6. The lug then strikes the cam edge 35^d and forces up the arm 35 releasing the paper returning spring in the manner already described, and forcing the point of 125 the V-shaped end of said arm slightly over dead center of the roller 37^a. The arm 39 is swung rearward again by its spring 40 into contact with said stud 41^a along with the tripping of the detent 27^a and resultant 130

start backward of the gear 24 and its lug 24^c, the arms 41 and 35 being held, however, in displaced position by reason of engagement between the roller 37^a and the V-shaped extremity 35^e of the lever 35. As the lug 24^c approaches the end of its return rotation, it strikes the front edge of the arm 39 which, owing to the lowered position of the rearward extension of the arm 35 and the correspondingly lowered position of the rear end of the arm 41, is slightly in advance of the shoulder 35^a of said arm 35 (Fig. 6^a). The arm 39 is at the time engaged with the stud 41^a so that the action 10 of the lug against said arm 39 effects upward movement of the arm 41 and consequently of the rearward extension of the arm 35 and thereby the shoulder 35^a of the latter is drawn down fully into the path of 15 the lug 24^c which lands against it so that the gear is stopped in its normal position illustrated in Fig. 4. This action at the outset carries the V-point 35^e upwardly across dead center of the roller 37^a so that 20 the spring 38 then aids in lowering the shoulder 35^e into full stopping position.

It remains to describe the release of the paper-returning spring by hand at the will of the operator whenever he desires to run 25 the paper back without the use of the tabulating key and without waiting for the gear 24 to complete a rotation; also the means whereby the platen may be disconnected from the spring and unlocked so as to permit 30 ordinary manipulation backward or forward to adjust the paper, or to permit employment of the machine without the paper-return feature.

The first of these things (Fig. 7) is accomplished by the simple expedient of pivoting upon the plate 13 at the point 43^a a hand lever 43 having an upwardly extending branch, given a right angle twist to provide a handle 43^b, and having a forwardly extending branch 43^c overlying the detent 27^a. This hand lever is normally upheld by a spring 44 connecting it with a stud 13ⁱ on the plate 13, said stud also serving to limit backward swing of this hand 45 lever. Obviously, a forward pull upon the handle of this lever will result in displacing the detent, as illustrated in Fig. 9, whereupon the platen will be run backward until the lug 24^c of the gear 24 lands against the 50 stop shoulder 35^a.

As to disconnecting the platen for paper adjustment or ordinary use of the machine, it has already been stated that the return mechanism is carried by a plate 13, which is 55 pivoted to the cradle 12. This provides for engaging and disengaging the gear 24 and pinion 10^a. A relatively strong spring 45 connects the said plate 13 and the rear portion of the cradle in such manner as to 60 swing the plate rearwardly and disengage

the gear wheel 24 from the pinion. (The upper end of said spring being attached to the same plate-stud 13ⁱ as the spring 44.) For the purpose of holding the plate forward in opposition to this spring and maintaining the engagement between the gear wheel and the pinion, I pivot upon the plate 13 at 46^a (Fig. 7) a latch 46 which is adapted to engage over a stud 12^a on the cradle, the engagement being enforced by a spring 46^b which connects the latch with the same stud 13ⁱ of the plate 13 to which the upper end of the spring 44 is attached. A handle 47 pivoted on the same stud which supports said latch projects conveniently 70 for manipulation and has a stud 47^a to operate upon an upward extension 46^d of the latch. The latter through a beveled formation at its forward end is designed to automatically engage over the stud 12^a when the plate 13 is forced forward. Obviously 75 rearward movement of the handle 47 will disengage the latch from said stud and cause the plate to swing rearwardly (Fig. 10).

Disengagement of the detent 27^a from the platen wheel 10^c as an incident to the rearward swinging of the plate is accomplished as follows: The hub 13ⁱ of the plate 13 is interlocked with the hub 48^a of an arm 48 (Fig. 11) which has a stud 48^b occupying a short slot 27^e in the detent 27^a. When the latter is engaged with the V-toothed wheel 10^c, as illustrated in Fig. 4, the said stud 48^b is at the lower end of said slot (dotted lines in said figure). Therefore, when the plate 13 is swung rearward under these conditions, the accompanying downward stroke of the arm 48 will result in disengagement of the detent 27^a from the wheel 10^c (Fig. 10). I also provide in this same 90 action for establishing the usual line-spacing control through engagement of a roll 50 with the V-toothed wheel 10^c. This roll in the present instance is mounted on the end of an arm 51 pivoted in the cradle and 95 drawn forward by a spring 52 but normally held away from the wheel 10^c by the arm 48, the latter being formed with a nose 48^d which engages a forward branch 51^a of said arm 51. Obviously when the arm 48 is 100 swung down as above described, the arm 51 is released and the spring 52 will then engage the roller 50 with the toothed wheel 10^c so as to establish the usual line-spacing 105 regulation while permitting the turning 110 backward or forward of the platen by the knob 10^e on the right hand trunnion thereof (Fig. 2). This customary engagement between the platen wheel and regulating roller would be undesirable when the automatic paper control is in commission because 115 of its interference with the easy running backward of the platen by the spring. It is unnecessary as a line-space regulator then because the detent 27^a serves the same pur- 120

pose. Obviously the equipment last above described provides for recording without the automatic paper-return attachment. The swinging back of the plate 13 does not 5 disturb the line-spacing connections from the shaft 100. It is limited by a stud 13^x engaging a slot 12^x in the side plate of the cradle.

I preferably regulate the speed of the paper-return so that it cannot become excessive, by a centrifugal governor. This is in 10 the form of a drum 60 secured against the inner side of the plate 13 (Fig. 2) and inclosing a set of segmental shoes 61 (Fig. 7) which occupy substantial quadrants of the 15 drum and are loosely arranged between radial pins or spokes 62. The latter are carried by a hub 63 secured to a shaft 64 which is journaled in the drum and in the plate 13, and on the outer side of the latter carries a pinion 65 (Fig. 4) in mesh with the gear wheel 24. Excessive speed of the latter 20 throws the shoes 61 outwardly against the inner wall of the fixed drum so that the gear is frictionally retarded.

25 Passing now to the matter of supporting a sheet of paper so that it may be readily fed into the machine and as readily run back, and referring more especially to Figs. 17-20, there is rigidly mounted upon the cradle 12 30 a sheet metal plate 90 extending the full length of the platen and a considerable distance upward, said plate being inclined rearwardly so as to support a sheet of paper in such manner that it will not likely fall forward over the machine. The said plate is 35 flanged at the ends and its upper rear portions connected by stay bars or braces 91 with forwardly projecting arms of the side pieces of the cradle. The plate is further 40 stiffened by an angle piece 92 which extends from side to side and is riveted against the back of the plate, as shown in Fig. 18. The plate is slotted crosswise on both sides of the central portion, as shown in Fig. 17, 45 to provide for lateral adjustment of angular guide plates 94 which lie against its front side. The outstanding flanges of these guide plates serve as guides for the side edges of the sheet of paper and it is of course 50 important that they shall always stand at right angles to the platen. For the purpose of insuring this and at the same time varying the adjustments of said guide plates I secure against the rear sides of the latter, 55 elongated metal blocks 95, which are rectangular in cross-section and occupy the horizontal slots 90^a in the back plate 90, the latter being flanged along the upper edges of said slots, as shown in Figs. 1, 7 and 10. 60 I form with or rigidly attach to the blocks 95 screw-threaded stems 95^a (Fig. 20) to which are applied thumb nuts 96 for the purpose of clamping the guide plates to the back plate. In order to do this most effectively I employ specially constructed

clamping pieces or clips 97 perforated to engage loosely over the screw-threaded stem 95^a between the blocks 95 and the bases of the screw nuts 96, and formed to engage closely over the flanges of the back plate 90 65 which extend along the upper sides of the slots 90^a, besides which said clips are also given a right-angled formation for close engagement with the under sides of the blocks 95. They also have somewhat extended flat portions to bear against the rear side of the back plate. It will be 70 obvious that the above described arrangement provides for very securely clamping the guide plates in position and insuring 80 the preservation of the proper right-angle relation between their outstanding flanges and the platen, while at the same time providing for an easy adjustment of the guide plates through the use of the thumb 85 piece 96,—all without recourse to upper and lower guide slots.

In order to provide for supporting the upper part of an extra long sheet I arrange 90 an extension piece 98 at the center of the plate 90, as shown in Figs. 17 and 19. Said plate 90 at its middle is given a trough-like formation, as shown at 90^a, and said extension piece is similarly shaped to slide therein, being slotted longitudinally to provide 95 for a wide range of adjustment. A screw 90^b in the upper portion of the trough of the plate 90 extends through said slot and its head engages over a friction piece 99 which overlies the edges of the slot so that the 100 tightening of a nut 90^c on said screw will hold the extension piece 98 in the position to which it is brought. The adjustment of said extension piece is facilitated by forming a finger piece 98^b at its upper end. 105

Of course it is not essential to the carrying out of my invention that a platen be employed for it is not so much the functioning of the roller as a platen that counts as its functioning for paper-feed purposes. 110 Therefore, in claims which follow the term "feed roller" is employed, so as not to restrict to a feed roller which is also a platen.

I claim:

1. The combination of a laterally shiftable paper carriage; a feed roller; a spring tensioned by advance movement of the latter; a detent for restraining said spring; a motor for shifting said carriage; a detent for holding the latter; and means for tripping the spring detent and the carriage detent. 115

2. The combination of a laterally shiftable paper carriage; a feed roller; a spring tensioned by advance movement of the latter; a detent for restraining said spring; a motor for shifting said carriage; a detent for holding the latter; and manipulative means for tripping the spring detent and the carriage detent. 120 125 130

3. The combination of a laterally shiftable paper carriage; a feed roller, a spring tensioned by advance movement of the latter; a detent for restraining said spring; a motor for shifting said carriage; a detent for holding the latter; means for tripping the spring detent and the carriage detent with provisions for delaying the release of the carriage until the feed roller has been rotated back-
wardly by said spring. 70
4. The combination of a laterally shiftable paper carriage; a feed roller; a spring tensioned by advance movement of the latter; a detent for restraining said spring; a motor for shifting said carriage; a tabulating stop on the carriage; a coacting relatively fixed stop; means for disengaging these stops and thereby displacing the spring detent; said means restraining the carriage in a slightly shifted position whereby upon restoration of said means to normal the carriage is shifted to the next columnar position. 75
5. The combination of a laterally shiftable paper carriage; a feed roller; a spring tensioned by advance movement of the latter; a detent for restraining said spring; a motor for shifting said carriage; a tabulating stop movably mounted on the carriage; a coacting fixed stop; means for displacing said tabulating stop and detaining the same and the carriage slightly shifted, and connections between said tabulating stop and the spring detent. 80
6. The combination of a laterally shiftable paper carriage; a feed roller; a spring tensioned by advance movement of the latter; a detent for restraining said spring; a motor for shifting said carriage; a tabulating stop pivoted on the carriage; a coacting fixed stop; a link connecting the said tabulating stop with the spring detent; and a manipulative shouldered member for displacing the said tabulating stop and detaining it and the carriage slightly shifted until release of said member. 85
7. The combination of a laterally shiftable paper carriage; a feed roller; a spring tensioned by advance movement of the latter; a detent for restraining said spring; a motor for shifting said carriage; a tabulating stop pivoted on the carriage; a coacting fixed stop; a link connecting the said tabulating stop with the spring detent; a pivoted arm having an abutment portion to act against and displace the tabulating stop and having a shoulder to detain the latter said shoulder offset relative to the fixed stop; and a key and connections for operating said arm. 90
8. The combination of a paper carriage; a feed roller; a spring tensioned by advance movement of the latter; a detent for restraining said spring; means for intermittently advancing the feed roller; and means for automatically tripping said detent as an incident to measured advance of said roller. 95
9. The combination of a paper carriage; a feed roller; a spring tensioned by advance movement of the latter; a detent for restraining said spring; means for intermittently advancing the feed roller; a gear turned by said roller; and means for automatically tripping said detent as an incident to said gear's completing a rotation. 100
10. The combination of a paper carriage; a feed roller; a spring tensioned by advance movement of the latter; a detent for restraining said spring; means for intermittently advancing the feed roller; a gear turned by said roller and having a lug; and an operating connection from the said detent acted upon by said lug. 105
11. The combination of a paper carriage; a feed roller; a spring tensioned by advance movement of the latter; a detent for restraining said spring; means for intermittently advancing the feed roller; a gear turned by said roller and having a lug; and an operating connection from the said detent acted upon by said lug and constituting a back stop for said gear. 110
12. The combination of a paper carriage; a feed roller; a spring tensioned by advance movement of the latter; a detent for restraining said spring; means for intermittently advancing the feed roller; a gear turned by said roller and having a lug; a lever shouldered to constitute a back stop for said lug and cam-related to the latter for displacement thereby under forward rotation of the gear; and an operating connection between said lever and the spring detent. 115
13. The combination of a paper carriage; a feed roller; a spring tensioned by advance movement of the latter; a detent for restraining said spring; means for intermittently advancing the feed roller; a gear turned by said roller and having a lug; a lever shouldered to constitute a back stop for said lug and cam-related to the latter for displacement thereby under forward rotation of the gear; an operating connection between said lever and the spring detent; and means operated upon by the lug in backward rotation to shift the lever to back-stopping position. 120
14. The combination of a paper carriage; a feed roller; a spring tensioned by advance movement of the latter; a detent for restraining said spring; means for intermittently advancing the feed roller; a gear turned by said roller and having a lug; a lever shouldered to constitute a back-stop for said lug and cam-related to the latter for displacement thereby under forward rotation of the gear; an operating connection between said lever and the spring detent; and spring-connected concentrically pivoted 125

arms one coupled to the lever and the other operated upon by the lug on backward rotation to shift the lever through the medium of the arm coupled thereto, said other arm yielding to the lug in forward rotation thereof.

15. The combination of a paper carriage; a feed roller; a spring tensioned by advance movement of the latter; a detent for restraining said spring; means for intermittently advancing the feed roller; a gear turned by said roller and having a lug; a lever shouldered to constitute a back stop for said lug and cam-related to the latter for displacement thereby under forward rotation of the gear; an operating connection between said lever and the spring detent; and means of a yielding character for enforcing full movement of the lever to its two extreme positions.

16. The combination of a paper carriage; a feed roller; a spring tensioned by advance movement of the latter; a detent for restraining said spring; means for intermittently advancing the feed roller; means for automatically tripping said detent as an incident to measured advance of said roller; and manipulative means for displacing the detent independently of said automatic tripping means.

17. The combination of a laterally shiftable paper carriage; a feed roller; a spring tensioned by advance movement of the latter; a detent for restraining said spring; a motor for shifting said carriage; a detent for holding the latter; means for tripping the spring detent and the carriage detent; and manipulative means for displacing the spring detent alone.

18. The combination of a paper carriage; a feed roller; a spring tensioned by advance movement of the latter; a detent for re-

straining said spring; means for intermittently advancing the feed roller; means for tripping the detent to cause backward turning of the feed roller by the spring; and means for disconnecting the latter from the feed roller at will with provisions for incidentally displacing the detent.

19. The combination of a paper carriage; a feed roller; a spring tensioned by advance movement of the latter; a detent for restraining said spring; means for intermittently advancing the feed roller; means for tripping the detent to cause backward turning of the feed roller by the spring; normally disabled line-space regulating means; and means for disconnecting the spring from the feed roller at will with provisions for incidentally displacing the detent and enabling the aforesaid line-space regulating means.

20. The combination of a laterally shiftable paper carriage; a feed roller; a spring tensioned by advance movement of the latter; a detent for restraining said spring; a motor for shifting said carriage; a detent for holding the latter; means for tripping the spring detent and the carriage detent; and means for automatically tripping the spring detent as an incident to measured advance of the said roller.

21. The combination of a paper carriage; a feed roller; a spring tensioned by advance movement of the latter; a detent for restraining said spring; means for intermittently advancing the feed roller; a settable signal for giving notice of a predetermined number of operations of said latter means; and means for tripping the detent.
